UNITED STATES PATENT OFFICE.

DANIEL McFARLAN MOORE, OF NEWARK, NEW JERSEY, ASSIGNOR TO MOORE ELECTRICAL COMPANY, OF NEW YORK, N. Y., A CORPORATION OF NEW YORK.

VACUUM-TUBE ELECTRIC APPARATUS.

1,008,728.

Specification of Letters Patent. Patented Nov. 14, 1911.

Application filed February 7, 1906. Serial No. 299,884.

To all whom it may concern:

Be it known that I, DANIEL McFARLAN MOORE, a citizen of the United States, and resident of Newark, in the county of Essex and State of New Jersey, with post-office address 52 Lawrence street, have invented certain new and useful Improvements in Vacuum-Tube Electric Apparatus, of which the following is a specification.

- 10 The present invention relates to vacuum tube or vapor electric lamps, vacuum or vapor rectifiers, X-ray tubes, vacuum oscillographs, wireless telegraph receivers and other devices which are provided with suitable electric terminals whereby electric energy may be passed through the gaseous contents of the tube for any purpose and which generally may be classified under the head of vacuum tubes.
- 20 In a previous application for patent filed by me Aug. 21st, 1905, I have described a method of maintaining a practically uniform gaseous condition within a vacuum tube by feeding gas from a source of gas under pressure in a determinate regulated amount into the tube through a restricted opening or openings or by means of a valve automatically governed by changes in the gaseous condition within the tube. As described in said application, the gas is fed from a pipe sealed to the tube at any point, although, I have shown it as consisting of a single feed tube connected to the vacuum tube at or about the middle thereof in order 30 to secure a more uniform distribution of the gas than would be possible if the connection were made near one end only.

- 40 My present invention consists among other things in feeding the gas into the tube at both ends thereof near the electrodes or in the case of a tube of great length to feed the gas into the tube at a number of points, in order that there may be a more even distribution of the gas fed into said tube.
- 45 To prevent a short-circuiting of the electric energy through the gas feed tube the terminals of which are connected to the tube at points across which a considerable difference of potential exists, I interpose 50 in said gas column finely divided non-conducting material either in solid or loose state, but preferably consisting of a mass of granular material, said material being pervious to the gas. When such material is 55 provided, I find that the tendency to short

circuiting of the electric discharge across the terminals of the vacuum tube and through said column may be effectually prevented even though a vacuum tube of very great length be employed and the column be 60 of very short length and connected across the ends of the vacuum tube near its electrodes. This particular expedient is not claimed herein as it forms the subject of claims in my application for patent filed 65 April 7, 1906, S. N. 310,408.

My invention consists further in certain details of construction and combinations of apparatus hereinafter more particularly described and then specified in the claims.

70 For the purpose of setting forth my invention, I shall describe the same as applied to a vacuum tube lamp into which gas is fed at both ends.

In the accompanying drawings, Figure 1 75 shows the apparatus in front elevation as assembled in a suitable danger proof box, the cover or lid of which is removed, the ends of the vacuum tube being shown in vertical cross section and other portions of the 80 tubing for feeding the gas being shown broken or in longitudinal section. Fig. 2 is a side elevation of the apparatus reduced in size one-half. Fig. 3 is a plan of the same apparatus. Fig. 4 is a general diagram of 85 the circuits and apparatus in one of its forms. Fig. 5 is a general diagram illustrating a modification of the circuits. Figs. 6, 7 and 8 show in detail various devices that may be used for positively determining 90 the rate of flow of gas into the tube without the use of any automatic valve action, but in a manner to maintain a practically uniform gaseous condition within the tube. Fig. 9 shows a modification wherein the 95 valve is worked by changes in the magnetic condition of the transformer, which supplies electric energy to the tube. Fig. 10 shows another form of valve which may be employed for feeding air or other gas to the 100 vacuum tube.

1 indicates the tube of glass containing air or other gas or vapor to be maintained in constant condition as to tension or other quality and which gas or vapor in the case 105 of a vacuum tube lamp is rendered luminous by the passage of the electric energy. The electrodes 2 are shown as internal electrodes, but might be external and are located within enlarged terminals of the tube 110

1. Said terminals together with the transformer or other devices supplying high tension energy to the tube are inclosed in a suitable insulating and fire-proof box or casing 18 from which the tube 1 of glass projects and extends to any desired distance and in any desired direction. 3 is a secondary of the transformer supplying high tension energy to the tube and 4 a primary connected to alternating current mains 5. The invention is not, however, limited to tubes run by alternating currents, but is also applicable to tubes operated by continuous currents. The terminals of the tube may be supported within casing 18 by suitable clips 19 as shown in Figs. 1 and 2.

20 is a tank located preferably in the box 18 and containing nitrogen or other gas according to the character of light desired. 20 Tank 20 is connected by a flexible or other pipe 21 with the vacuum tube through devices for feeding the gas from the tank in the determinate or regulated amount necessary for keeping the gaseous tension within the tube constant.

22 is a chamber also by preference located in box 18 and containing an air drier such for instance as chlorid of calcium and a filtering material such for instance as cotton packed in the ends of the chamber and inclosing the chlorid of calcium. Air may be taken through said chamber 22 and stopcock 23 to a flexible pipe 21' from which it may be delivered in the regulated amount to the vacuum tube as will be desired. Obviously the air drier might be placed at any desired point in the connections leading from the source of gas to the tube.

6 is a tube into which the air or gas is slowly and gradually fed and from which it passes into the vacuum tube 1 at any desired point or points. It is desirable to feed the air or gas into the vacuum tube at both ends thereof, especially when said tube is of great length in order to obtain a uniformity of gaseous condition throughout the tube and prevent it, in the case of a lamp, from being brighter at one end than at the other. To accomplish this, the tube 6 branches into the tubes 6' connected to the vacuum tube as shown within the box 18. When the tube 1 is of great length, there would be a tendency to diversion of the electric energy from one terminal of the vacuum tube to the other through the comparatively short length of tubing 6', whose ends connect at points between which there is a great difference of electrical potential. To avoid this, a mass of material 24 pervious to gas is located in the gas passage through which said energy may tend to pass without circulating through the vacuum tube. Said mass of material 24 may be solid or subdivided mechanically, but is preferably a mass of granular material of an insulating

character such for instance as fine beach sand. This material is pervious to the air or gas but acts to prevent the diversion of the electric energy through the connecting tubes 6'. It also acts to prevent the high potentials from working back from the vacuum tube through the feed tube or tubes to the valve and tank. A packing 26 of fibrous material, preferably glass fiber, may be used to retain the sand or other granular material in place.

The feeding of the air or gas into the tube 6 in the requisite amount or at the desired rate may be produced by the use of a valve acting to close or open a port or passage, one or more in number, and said port or passage or passages may be through a mass of porous material, immersed in a liquid like mercury, whose level is changed to produce a valve action or said valve may be a valve composed wholly of solid material as will be presently described. The slow or regulated feed may also be produced by permitting the air or gas to flow or percolate constantly through a mass of porous material or through a minute opening or leak of any character as for instance at the edge of the port in a plug or tapered valve, whose faces are well-oiled so as to secure the presence of a film of oil for the gas to pass through.

In case the feed of the gas is controlled by valve action, the following valve construction may be used: 7 is a mass of porous material preferably consisting of rather dense arc light carbon. The denser the carbon, the less the length of the mass 7 through which the gas is required to pass. The mass 7 is seated as a stopper in the end of a tube 8 joined to tube 6 and located in a chamber 9, preferably of glass, forming a valve chamber with which tube 21 or 21' connects. In the chamber 9 is a body of liquid such as mercury surrounding the mass of porous material 7 and leaving the upper terminal of the same exposed or adapted to be exposed by a slight change of level of the liquid 11 brought about in any desired way, as for instance, by the operation of a plunger or liquid displacer 10 immersed in the liquid. Displacer 10 consists of a tube of glass having an opening in its side to admit the air or gas to the space above the tip of the carbon 7. By moving the displacer, the tip of the mass 7 may be more or less exposed, or by a suitable adjustment may be alternately exposed and sunk beneath the level of the liquid so as to vary the extent of the porous surfaces through which gas under pressure may leak into and through the mass 7. As indicated in Fig. 6, the mass might have its tip constantly exposed, the minute leakage being determined by the small size of the tip and the length of the mass. It is preferred to

taper the point of the tip for the purpose of securing a marked change in the extent of exposure for a small change in the level of the liquid. Inasmuch as the plunger 5 works in the same body of liquid in which the tip of the valve proper is located and is exposed to the same pressure of incoming gas, it is obvious that any changes in such pressure will not affect the height of the 10 liquid so as to disturb the adjustment of the valve and the same will, therefore, work in a uniform manner in response to the action of the magnet and irrespective of variations in the pressure of the body of gas 15 constituting the source of supply.

The displacer 10, Fig. 1, may be operated by means of an electromagnet 16, the laminated core of which indicated at 12, is held in a tubular extension of the tubular displacer 10 by a contraction 13. The tube or 20 chamber 9 is supported within the casing 18 by clips 17. An adjustment of the vertical position of the displacer to determine the extent to which the tip of the mass 7 shall 25 be normally exposed above the level of the liquid may be secured by adjusting the position of the coil 16 of the electromagnet vertically on the tube 9 by means of a screw 15. Mercury is preferred because it forms 30 an effective air seal and does not clog the pores of the porous mass 7.

The automatic action of the valve thus constructed and in response to change of gaseous condition within the tube 1 may be 35 obtained by connecting the electromagnet 16 to the electric circuit of the lamp either by placing it in the primary connection from the constant potential mains 5 as shown in Fig. 4 or by connecting it into the secondary 40 circuit of the transformer as shown in Fig. 5. As is well known, there is a critical tension or degree of vacuum in the tube at which the resistance to the passage of electric energy through the gas from one electrode to the other of the tube is at its lowest. 45 If the vacuum increases beyond this critical point, the resistance increases below the degree of vapor or gas tension at which the resistance and current change from a decreasing value of resistance and increasing 50 value of current, but for economy the degree of vacuum should be maintained as near as possible to the point where the resistance is least, though sufficiently below 55 such point to avoid the possibility of changes of tension extending over to the degree where the resistance will increase with an increase of the vacuum. When then the 60 vacuum in the lamp becomes slightly higher through continued action of the electric energy upon the gaseous contents, and the resistance decreases, slightly more current flows through the magnet which thereupon causes the height of the liquid level to fall 65 by lifting the displacer 10. This permits

gas to flow through the tip of the plug or pencil 7 into the lamp until the normal gaseous condition therein is restored so that the magnet will let the displacer 10 fall again.

The transformer may be either what is known as the core type as shown in Fig. 9 or the shell type as indicated in Fig. 10 and may be supported in a frame 37 within the casing 18. The core 12 which operates the 75 valve instead of being operated by a coil 16 independent of the transformer, may be operated by changes of magnetic condition in the transformer itself as indicated in these Figs. 9 and 10 in which cases it is 80 located in an opening or partial break in the magnetic circuit 29 of the transformer and is lifted by any increase in the lines of force flowing. By this means the transformer is made to operate also as an effective steadyinductance since the increased current flow through the tube, which brings the core 12 into action to operate the valve, also produces an increase in the self-inductance of the transformer itself thereby cutting down the flow of current to the tube. 90

In Fig. 10 a simple form of valve having no liquid is shown. 32 is a plug of brass or other metal closing the end of tube 6, through which air may be fed to the vacuum tube. Said plug 32 is centrally perforated and the mouth of the perforation is closed when no air flows by a disk 33 which is made preferably rather of some hard vulcanized rubber. This disk has a perfectly flat face 100 adapted to rest upon the tapered end of plug 32 and is carried by the block 31 sliding in guides and attached to the end of the core 12. The latter works in a guide in the transformer core and is depressed by a spiral spring 40 aided by gravity to close the valve. Screw 41 adjusts the action of the spring. The valve is opened by increase in the magnetic lift upon the core 12. The frame 30 attached to the core 29 supports plug 32 and guides. As shown the device feeds air but by inclosing the parts to form a valve chamber and connecting said chamber with a tank, any desired gas may be fed to tube 6 105 and to the vacuum tube. 110

Referring to Fig. 1 and the form of valve shown therein, it will be obvious that the constancy of condition in the tube 1 can be maintained by an adjustment of the parts such that each excursion of the plunger to and fro will result in an uncovering and complete covering of the tip of the plug or the tip may be at all times exposed and the action be by an increase and decrease of the amount of tip that is exposed. By placing a stop-cock 25 in the connection between the valve and the lamp, it is practical to produce a portable apparatus. That is, after the tube is placed in operative condition at 120 the factory, stop-cock 25 is turned off, the 125 130

tube, as a whole, inverted, or by other means the mercury 11 is removed. This permits the gas pressure to become high up to the stop-cock 25. When the lamp is again set up for use after shipment, the correct amount of mercury is first poured into the glass tube 9 and then the stop-cock 25 is very gradually opened, that is, by slow stages, so that the tube gradually uses up the air which was entrapped between the bottom of the porous plug 7 and the stop-cock 25. After it is all used up, which can be determined in a number of ways, but principally by the appearance of the light, the stop-cock 25 will be turned on full, and the feeding of the gas to the tube will then become automatic, as before described. The gradual adjusted flow may be obtained without movement of the valve by using a stop-cock 28, Fig. 7, and setting the same so that the edge of the port running through it will be near to the edge of the port in the valve body, so as to permit an extremely slight leak through the film of oil or grease on the adjacent surfaces, a slow and continuous flow of gas in the requisite amount to maintain the standard gaseous condition in the tube may be produced. The same action might be secured by the peculiar form of valve shown in Fig. 8 in which the port or hole corresponding to port is packed with porous material through which the gas will slowly percolate to the desired degree determined by the extent to which the end of the porous plug is exposed at the port in the valve body.

34 indicates an inductive resistance interposed preferably in the primary circuit of the transformer for the purpose of steady-ing the light. This inductive resistance is supported in a frame 36 within the casing 18 and is of the shell type. Its two coils 35 are in series with one another and are wound to produce a consequent pole between them in the core or portion of the core to which they are applied, and are adjustable to and from one another. By this adjustment to vary the magnetic leakage the self inductive effect of the coils may be varied and the in-

tensity of the light regulated to a certain extent. In some cases, the device 34 may be omitted and the self induction of the coils 16 may then afford the steadyng resistance.

As shown in Fig. 9 the steadyng resistance, the transformer and the means for actuating the valve may be combined in one instrument. By locating the gas tank, which is preferably of metal, within the casing 18, the danger of fire or of damage from contact with said tank arising from accidental working back of the high potentials through the tubes or passages connecting the vacuum tube and tank, is effectually avoided. The said box or casing 18 is in fact a danger proof box or case and by the location of the transformer and other parts which may have the required high potential of its secondary within said box, the apparatus is made to meet the requirements of fire underwriters and is free from objection on the score of possible fire or harm to persons touching the parts.

In the foregoing description and in the claims appended, the term "gas" is to be understood as including the aeriform condition of any solid or liquid and commonly known as vapor.

What I claim as my invention is:

1. The combination of a vacuum tube, means for feeding gas into said tube at both ends thereof and means for regulating the admission of the gas by an automatic valve action controlled through changes of the gas or vapor tension within the tube.

2. The combination with a vacuum tube operated by alternating currents, of a steadyng inductance of the shell type having a pair of coils adjustable with relation to one another on the magnetic circuit of the inductance, as and for the purpose described.

Signed at New York in the county of New York and State of New York this 22d day of January A. D. 1906.
